TAG HOLDER

Walter E. Waechtler, San Francisco, Calif.

Application July 31, 1933, Serial No. 682,918

5 Claims. (Cl. 40—11)

This invention relates to improvements in tag holders and more particularly to means for attaching tag holders to supporting members.

The present disclosure has to do with the application of a tag holder to portable cans or containers for petroleum and other liquid products.

For instance, in making tank wagon deliveries, the driver often fills similar containers with products having confusing characteristics such as gasoline, naphtha and the like easily distinguishable only by proper designation of the containers.

Such containers being of standardized construction and in use in great numbers, there has heretofore been no convenient means for attaching identifying tags thereto.

Among the objects of the invention is to provide a simple tag holder that can be easily and rigidly attached by unskilled persons with the aid of common tools.

20 Another object is to provide a tag holder that may be used as a tag hanger or as a spring clamp to hold records relating to the contents of the container such as bills, formulas and the like.

Other objects and advantages will appear as 25 the description progresses.

In this specification and the accompanying drawing, the invention is disclosed in its preferred form. It is to be understood, however, that it is not limited to this form because it may be 30 embodied in other forms without departing from the spirit of the invention as defined in the claims following the description.

In the one sheet of drawing:

Fig. 1 is a front elevation of the upper portion 35 of the conventional pouring can or container for motor spirit such as gasoline, having this invention applied thereto.

Fig. 2 is an enlarged fragmentary detail of the bail or handle of the same.

40 Fig. 3 is a side elevation of the same.

Fig. 4 is a plan view from above in horizontal section, see IV—IV, Fig. 3, illustrating one way of attaching the holder using the conventional pliers shown in dotted lines.

45 Fig. 5 is a fragmentary detail showing a different location of the holder on the bail whereby it acts as a spring clamp to hold a paper card.

In detail the construction illustrated in Fig. 1 comprises the metal can body 1, having the tapered top 2, the neck 3 and the friction cap 4 with the handle 5.

50 The brackets 6 and 7 are fixed to the body of the can top on opposite sides. The bail 8 is usually formed of a flat strip of metal having its opposite ends pivoted to the brackets at 9 and 10 with its

center portion formed to provide a comfortable hand grip at 11. These brackets have the lugs 12 and 13, respectively, which prevent the bail dropping below a horizontal position.

Broadly stated, the present invention consists of a bendable metal clip having a hook thereon and adapted to be easily clinched around the bail of the can or other support.

This clip 14 is preferably die stamped and formed from a narrow strip of metal such as 10 mild steel. It has the upset portion 15 bent therein intermediate its length. The apex of this upset portion has two interspaced holes therein adjacent the edges of the clip.

Intermediate the width of the clip 14, on each 15 side of the channel 15, it has the round holes 16 and 17, across the diameter of which it is bent at right angles, see Fig. 4, to form a U shape the width of the bail strip 8. The two ends 18 and 19 are then bent around the bail and flattened 20 as in Fig. 5 to permanently fix the clip upon the bail at the desired position. The holes 16 and 17 weaken the clip and form the enfolding straps 20—20 and 21—21 bent around the rounded edges 25 of the bail and insure the bending of the clip at exactly the right point without spring back to insure the clip 14 against lateral movement on the bail.

The hook 22 may be an integral extension of the upset portion 15 but the present structure 30 is preferred by the principal consumers of this product.

This hook is formed in dies with the bent back end 23, the shank 24, and the upturned head 25. The hook is preferably assembled in the clip before its attachment to the bail. This is done by pushing the hook 22 through the top hole 15' in the clip until the shank 24 lies in the socket formed by the upset portion 15 with the other 35 end of the hook projecting through the lower hole 15' in the upset portion. This short end is then riveted or beaded over to form the head 25 which holds the hook in the clip under the tension due to the oblique extension of the hook shank through the hole 15'. This shank may be welded or otherwise secured in the channel.

40 The advantage of the assembled hook over the hook integral with the clip is the choice of materials suitable for the hook such as spring brass wire which is harder and stronger than any softer material suitable for the clip 14, such as mild steel.

45 In the form shown in Fig. 5, the clip is mounted lower on the bail so that the end 23 yieldingly bears against the adjacent plane of the bail 8 55

with sufficient tension to clamp a card x therebetween; as compared with the preferred form in Figs. 1 and 2 upon which a metal tag x' may be detachably suspended.

5 Having thus described this invention, what is claimed and desired to secure by Letters Patent is:

1. A tag holder having a bendable clip with a center upset portion and flat portions extending 10 on each side of said upset portion and holes through the flat portions of said clip, and adapted to be bent across said holes and engage a supporting member; and a hook fixed in said upset portion.

15 2. A tag holder having a clip adapted to engage a supporting member and having a center upset portion with interspaced holes through the walls thereof; a hook having a shank in said upset portion and extending through said holes and 20 riveted to said clip.

3. A tag holder having a bendable clip with a transverse upset portion having a hole through the wall thereof and holes through said clip on opposite sides of said upset and adapted to be bent

across said holes and engage a supporting member; and a hook having a shank in said upset and an end extending through the hole through the wall of said upset.

4. A tag holder comprising a bendable clip with a central upset portion and flat portions extending on each side of said upset portion; and a hook having a shank fixed in the upset portion of said clip; said clip being adapted to have its flat portions bent around a supporting member with the shank of said hook in the upset portion interposed between said clip and said supporting member. 5

5. A tag holder comprising a bendable clip with a central upset portion and flat portions extending on each side of said upset portion; and a hook having a shank extending along the channel formed by the upset portion of said clip; said clip being adapted to have its flat portions bent around a supporting member with the shank of said hook 10 15 20 confined between said channel and said supporting member.

WALTER E. WAECHTLER.
